BRASSIÈRE

Tina Leser, New York, N. Y.

Application November 5, 1949, Serial No. 5,887

Term of patent 14 years

(Cl. D20—4)

To all whom it may concern:

Be it known that I, Tina Leser, a citizen of the United States, residing in New York city, in the county of New York and State of New York, have invented a new, original, and ornamental Design for a Brassière, of which the following is a specification, reference being had to the accompanying drawing, forming part thereof.

Fig. 1 is a plan view of the face of a brassière showing my new design,

Fig. 2 is a plan view of the inner face,

Fig. 3 is a front view, on a larger scale, as it appears in wearing position, and

Fig. 4 is a rear view thereof.

I claim:

The ornamental design for a brassière, substantially as shown.

TINA LESER.
